UNITED STATES PATENT OFFICE.

CULLEN D. WHITE, OF UNION CITY, TENNESSEE.

THILL-SUPPORT.

SPECIFICATION forming part of Letters Patent No. 758,160, dated April 26, 1904.

Application filed February 27, 1904. Serial No. 195,622. (No model.)

To all whom it may concern:

Be it known that I, CULLEN D. WHITE, a citizen of the United States, residing at Union City, in the county of Obion and State of Tennessee, have invented a new and useful Thill-Support, of which the following is a specification.

This invention relates to devices for attachment to vehicles for supporting the shafts or thills in an elevated position when not in use, and has for its object to provide a simply-constructed and inexpensive device of this character attachable to any style or form of buggy, carriage, or similar vehicle and by means of which the thills may be supported in an elevated position and quickly released when required.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages, and the right is therefore reserved of making all the changes and modifications which fairly fall within the scope of the invention and the claims made therefor.

In the accompanying drawings thus employed, Figure 1 is a perspective view of the improved device applied. Fig. 2 is a perspective view from the rear of the improved device detached and enlarged.

The improved device may be attached to any suitable portion of the forward running-gear to bring it in proper position relative to the thills or shafts and for the purpose of illustration is shown attached to the upper spring bar or bolster 10, which will preferably be se-

lected when the construction of the vehicle 50 running-gear permits of it.

The improved device consists of a bracket or frame having a vertical arm 11 terminating in a lateral stop 12 and a horizontal arm 13 terminating in a lateral stop 14, with the extremities of the arms connected by a guard member 15, preferably segmental in form. The bracket is provided with a clip 16, by which it may be detachably connected to the bolster-plate 10 or other suitable portion of the vehicle, and this portion of the device, it is obvious, may be varied to adapt it to different classes and forms of vehicles without in any manner affecting the principle of the invention, which is not necessarily dependent upon any particular means for attaching it to the vehicle. A stop-bar 17 is pivoted at 18 to the bracket for swinging into engagement alternately with the stop-arms 11 13 and lateral stops 12 14 and limited in its movement 60 in one direction by the guard member 15.

The device will be so positioned relative to the thills (represented at 19) that when elevated it will extend in front of some portion of the same and maintain them in an elevated 75 position and when depressed into engagement with the arm 13 and its stop 14 will release the thills and permit them to be lowered into operative position.

Check-springs 20 21 will be attached, respectively, to the vertical member 11 and lateral stop 14 to bear upon the bar 17 and maintain it yieldably in either one of its two positions and prevent accidental displacement of the bar.

By this simple means it is obvious that a very effective and convenient device is produced applicable to any style or form of buggy or similar vehicle and by means of which the thills may be securely supported when not in use.

The guard member 15 is an important feature of the invention, as it affords a firm support to the members 11 and 13 and also firmly supports the bar 17 at all points in its travel 95 and relieves the pivot 18 very largely from strains.

The parts 11 and 13, together with the main

portion 16 of the clip and stops 12 14 and guard member 15, will preferably be in one single casting of steel or malleable iron and of suitable strength to resist the strains to 5 which they will be subjected.

Having thus described the invention, what is claimed is—

1. A device of the class described, consisting of a bracket for detachable connection to the running-gear of a vehicle and having a vertical arm and a horizontal arm each with a lateral stop, and a stop-bar pivoted to said bracket and swinging across the path of the thills when elevated and supported alternately 15 in its elevated and depressed positions by said arms and their lateral stops.

2. A device of the class described, consisting of a bracket for detachable connection to the running-gear of a vehicle and having a vertical arm and a horizontal arm each with a lateral stop, a stop-bar pivoted to said bracket 20 and swinging across the path of the thills when

elevated and supported alternately in its elevated and depressed positions by said arms and their lateral stops, and a segmental guard connecting the extremities of said stop-arms. 25

3. A device of the class described, consisting of a bracket for detachable connection to the running-gear of a vehicle and having a vertical arm and a horizontal arm each with a lateral stop, a stop-bar pivoted to said bracket 30 and swinging across the path of the thills when elevated and supported alternately in its elevated and depressed positions by said arms and their lateral stops, and check-springs connected to said stop-arms to yieldably maintain 35 said stop-bar in its two positions.

In testimony that I claim the foregoing as my own I have hereto affixed my signature in the presence of two witnesses.

CULLEN D. WHITE.
